FLUID PRESSURE MECHANISM

Elbert Fowler, Mount Vernon, N. Y., assignor to
 BENDIX-WESTINGHOUSE AUTOMOTIVE AIR BRAKE
 COMPANY, ELYRIA, OHIO, A CORPORATION OF DELA-
 WARE

Application August 4, 1943, Serial No. 497,387

19 Claims. (Cl. 230—2)

This invention relates to fluid pressure control systems and more particularly to mechanism for producing fluid pressure under substantially high pressures and for controlling the maintenance of these pressures.

The present invention contemplates a mode of operation wherein the intake side of the fluid compressor is normally maintained at a pressure well above atmospheric pressure, this mode of operation permitting the compressing of fluids to a relatively high pressure at the output side of the compressor without resulting in correspondingly increased compression ratios, such as would occur in the event such a high pressure were obtained from a single stage compressor in the ordinary manner. In addition to the foregoing, the present invention contemplates a system wherein, after the system has been initially charged with a fluid pressure, the system automatically becomes a closed system, no further fluid being drawn into the compressor from an outside source except such fluid as is necessary to compensate for leakage from various parts of the system, systems of this nature being particularly applicable to the compression of fluid under conditions such that moisture present in the fluid normally has a very detrimental effect on the operation of the system, an effect which is largely minimized by the present invention.

It has previously been proposed to provide so-called closed systems for the compression of air or other gas in order to prevent the accumulation of excessive moisture in the system such as might be drawn in from the atmosphere, but difficulty has been experienced in systems of this type in properly controlling the pressures in the low and high pressure portions of the system, and it is accordingly an object of the present invention to provide means for controlling the pressures in the system without unnecessary attention on the part of the operator.

Another object of the invention is to provide in a fluid compressing system of the above type, means for maintaining the intake side of the compressor at a pressure above that of the surrounding atmosphere.

Yet another object of the invention is to provide means for controlling the relative pressures in the high and low pressure portions of the system and for maintaining them at substantially predetermined values.

Still another object of the invention is to provide in a system of the above type, means for supercharging the compressor at a pressure con-

siderably above that of the surrounding atmosphere.

Another object of the invention is to provide control mechanism for a compressor so constituted as to permit the supplying of high pressure air to one receiver and low pressure air to another receiver by means of a single stage compressor.

A further object of the invention is to provide, in a system of the above type, means for preventing further compression of fluid by the compressor when the desired predetermined pressures are established in the high and low pressure portions of the system.

A still further object of the invention is to provide a system of the above type so constituted as to permit the controlled pumping of relatively high pressures with a single stage compressor without the necessity for utilizing correspondingly high compression ratios.

These and other objects and novel features of the invention will appear more fully hereinafter from the following detailed description when considered in connection with the accompanying drawings illustrating two embodiments of the invention.

It is to be expressly understood, however, that the drawings are employed for purposes of illustration only and are not designed as a definition of the limits of the invention, reference for the latter being had to the appended claims.

In the drawings, wherein similar reference characters denote corresponding elements throughout the several views:

Fig. 1 is a diagrammatic illustration, partially in section, of a fluid compressing system embodying the principles of the present invention, and Fig. 2 is a diagrammatic illustration, partially in section of another embodiment of the invention.

Referring more particularly to Fig. 1 of the drawings, a fluid compressing system embodying the present invention is illustrated therein as including a high pressure reservoir 6 and a low pressure reservoir 7, together with a compressor 8, which may be of the well-known rotary type, and which is adapted to supply fluid pressure to the high and low pressure reservoirs as will be more fully explained hereinafter. The compressor 8 includes a casing 9 having a bore 10 and a rotor 11 adapted to be driven in a counter-clockwise direction by a suitable prime mover, not shown, the rotor being provided with sliding blades 12 in contact with the wall of the bore 10, which is of the so-called generated

type, and since this compressor is of well-known construction, it will be understood that on operation of the rotor, fluid will be transferred from an intake port 13 provided in the casing of the compressor to a discharge port 14, the fluid at the same time being compressed to a degree dependent on the design of the compressor mechanism. The inlet port 13 is provided with a connection to atmosphere which includes a passage 15 and an atmospheric port 16, communication 10 between the inlet port and the passage 15 being normally prevented by means of a check valve 17 normally maintained in engagement with a valve seat 18 formed at the lower end of the passage 15, through the medium of a spring 19 interposed between the compressor casing and the lower face of the valve. The discharge port 14 is connected with the high pressure reservoir 6 through the medium of an outlet chamber 20 and a conduit 21 interconnected between the chamber and the reservoir, a check valve 22 normally maintained in engagement with a valve seat 23 formed at the upper end of the discharge port 14 by means of a spring 24 interposed between the upper face of the valve and a portion of the casing serving to permit passage of fluid from the compressor to the high pressure reservoir and to prevent the passage of fluid in the other direction from the reservoir to the discharge port of the compressor. A second outlet chamber 25 is provided as shown, this chamber being provided at its upper end with a port 26 and at its lower end with a port 27, the port 27 being connected with the discharge port 14 through the medium of a passage 28 formed in the cas'ng. In order that fluid pressure may be supplied from the compressor to the low pressure reservoir 7, the second outlet chamber 25 is connected thereto through the medium of conduit 29, port 26 at the upper end of the outlet chamber 25 being connected with the inlet port 13 of the compressor through the medium of a passage 30 and a passage 31 formed in the casing and connected thereto. In order that the connections between the inlet and outlet ports of the compressor and between these ports and the high and low pressure reservoirs may be properly controlled, the outlet chamber 25 is provided with a valve 32 provided with an upwardly extending stem 33 slidably mounted in a bore 34 formed in the upper portion of the housing, the valve being normally maintained in the position shown to close the port 27 by means of a spring 35 interposed between the upper end of the casing and a flange 36 formed on the stem of the valve, the tension of the spring 35 being sufficient to maintain the valve 32 in a position to close the port 27 regardless of the degree of pressure existing in the passage 28 connected with the discharge port 14. With the parts in the position shown, it will be understood that operation of the compressor will serve to draw fluid into the intake port 13 through atmospheric port 16, passage 15 and check valve 17, and to compress this fluid in discharge port 14, whereupon the fluid forces its way past the check valve 22 and thence through the outlet chambers 20 to the high pressure reservoir 6 through the medium of the conduit 21.

Assuming that it is desired to limit the pressure in the high pressure reservoir to 600 pounds, for example, means are provided under the control of the pressure in the high pressure reservoir for changing the position of the valve 32 when this predetermined pressure is reached,

such means including a pressure-responsive governor 37 of well-known design, a relay valve mechanism 38 and a fluid pressure actuator mechanism 39 adapted to be controlled by the operation of the governor 37. As will be well understood by those skilled in the art, the governor mechanism 37 is provided with a conduit 40 connected with the reservoir 6 and an outlet conduit 41, together with an atmospheric port, not shown, the governor serving normally to establish a connection between the conduit 41 and the atmospheric port and to prevent communication between the supply conduit 40 and the outlet conduit 41. The governor may be adjusted to operate over a predetermined pressure range, and in the event a maximum pressure of 600 pounds is desired in the high pressure reservoir, the governor may be set in such a manner that when this pressure is reached, the governor will operate to disconnect the conduit 41 from the exhaust port of the governor and to establish a connection between conduits 40 and 41, thus supplying fluid pressure to the conduit 41 through the governor at the pressure attaining in the reservoir 6. On a reduction of pressure in the reservoir 6 to 590 pounds, for example, the governor again becomes operative to dis-establish the connection between conduits 40 and 41 and to establish a connection between conduit 41 and the atmospheric port, thus permitting fluid in the conduit 41 to exhaust to atmosphere.

The mechanism 39 is for the purpose of controlling the operation of the valve 32, the mechanism comprising a fluid motor 42 having an inlet chamber 43 and a piston 44 slidably mounted therein and provided with a piston rod 45, together with a second fluid motor 46 provided with an inlet chamber 47, a piston 48 and a piston rod 49 connected thereto. In order that the fluid motors may serve to control the operation of the valve 32, a beam 50 is pivotally connected to the upper ends of both the piston rod 45 and the piston rod 49 by means of pivot pins 51 and 52 respectively, the upper end of the valve stem 33 being pivotally connected to the beam by the means of a pin 53 at a point intermediate the pins 51 and 52. Thus the spring 35 acting on the valve stem 33 in conjunction with pivot 53, beam 50, and pivot pins 51 and 52 serve to normally maintain the pistons 44 and 48 in the position shown with respect to the inlet chambers 43 and 47, the upward travel of the piston rod 45 being limited by means of a stop 54, and the upward travel of the piston rod 49 being limited by means of a stop 55, the spacing between the upper end of the rod 49 and the stop 55 being such that on upward movement of the piston 48 and rod 49 only, the beam 50 will pivot about the pin 51 on the piston rod 45, and the valve stem 33 will move upward sufficiently to move the valve 32 through only half the distance between the upper end of the port 27 and the lower end of the port 26, downward movement of the rod 45 and the piston 44 being prevented by the abutment of the lower face of the piston against the lower end of the chamber 43. The spacing between the stops 54 and 55 and the ends of the piston rods 45 and 49 respectively is also so chosen that in the event both piston rods are moved upward, the movement imparted to the valve stem 33 will be sufficient to move the valve 32 against the lower end of the port 26 before motion of the rod is prevented by the stops 54 and 55, upward movement of one of the piston rods

only thus serving to move the valve to the half-way position, and concurrent or sequential movement of both piston rods serving to move the valve to its extreme upward position through the connections described.

The relay valve mechanism 38 is for the purpose of controlling the supply of fluid pressure to the motor 42, the mechanism being provided with an outlet chamber 56 having a connection with the chamber 43 of the motor 42 through the medium of a conduit 57, and an inlet chamber 58 to which is connected the conduit 41 leading to the governor 37. The chambers 56 and 58 are normally connected through the medium of a port 59 formed in a partition 60 which serves to separate the chambers, while the outlet chamber 56 is adapted to be connected with atmosphere through the medium of a port 61 formed in the wall of the outlet chamber. In order that the connection between the inlet and outlet chambers and between the outlet chamber and atmosphere may be properly controlled, a valve stem 62 is slidably mounted in the casing of the relay valve, the stem being provided at its upper end with a valve member 63, and at its lower end with a piston 64 mounted in a cylinder 65 formed in the lower portion of the casing, a spring 66 interposed between the lower end of the cylinder 65 and the lower face of the piston serving normally to maintain the piston, rod and valve in upward position wherein the port 59 is open to permit communication between the inlet chamber 58 and the outlet chamber 56 and the atmospheric port 61 is closed by the upper end of the valve 63. Thus with the parts in the position shown, operation of the governor 37 to establish a connection between conduits 40 and 41 will serve to supply fluid pressure to the chamber 43 of the motor 42 through the chamber 58 of the relay valve, port 59, outlet chamber 56 and conduit 57, the fluid pressure thus supplied to the motor 42 serving to move the piston 44 and the rod 45 upward against the stop 54 to move the valve 32 to mid-position. The chamber 41 of the fluid motor 46 is likewise connected with the conduit 41 through the medium of a conduit 67, and thus operation of the governor 37 to supply fluid pressure to the motor 42 will likewise supply fluid pressure to the motor 46, causing the piston 48 and the rod 49 to move upward at substantially the same time as the piston 44 and the rod 45 of the motor 42, with the result that the valve 32 will be moved upward to close the lower end of the port 26, thus establishing communication between the outlet chamber 25 and the discharge port 14 of the compressor through the passage 28 and serving to prevent communication between the outlet chamber and the inlet port of the compressor through the passage 30 and the passage 31. Thus when the pressure in the high pressure reservoir reaches a pressure of 600 pounds, for example, the valve 32 will be moved to its extreme upward position in the manner just described, whereupon, the fluid pumped by the compressor will be supplied to the low pressure reservoir 7 through the passage 28, port 27, outlet chamber 25 and conduit 29.

With the above pressure prevailing in the high pressure reservoir 6, it may be desirable to maintain a maximum pressure of approximately 100 pounds in the low pressure reservoir 7 in order that the compressor may operate on a relatively small compression ratio, and in this case means is provided for controlling the operation of the relay valve 38 to render the compressor ineffec-

tive to supply fluid pressure to either of the reservoirs, this mechanism including a second governor 68, which may be of similar construction to the governor 37, the governor being supplied with fluid pressure from the reservoir 7 through the medium of conduit 69 and serving to supply fluid pressure to a portion of the relay valve 38 through a conduit 70, it being understood that when a pressure of 100 pounds is reached in the reservoir 7, the governor 68 will become operative to dis-establish a connection between the conduit 70 and the atmospheric port of the governor, not shown, and to establish a connection between the supply conduit 69 and the conduit 70, thus supplying pressure from the reservoir 7 to the conduit 70. The relay valve mechanism 38 is provided with a chamber 71 above the piston 64, and on operation of the governor to supply fluid pressure to the conduit 70, fluid pressure is also supplied to the chamber 71, connected thereto, resulting in downward movement of the piston against the spring 66, and consequent downward movement of the valve 63 to open the port 61 and close the port 59. When this action occurs, fluid pressure will be exhausted from the chamber 43 of the motor 42 through conduit 57, chamber 56 of the relay valve 38 and exhaust port 61, whereupon the spring 35 will force the valve stem 33 and the beam 50 downward until the piston 44 abuts the lower end of the fluid motor 42, whereupon the valve 32 will be in mid-position between ports 26 and 27 and the discharge port 14 will be in communication with the inlet port 13 of the compressor through the passage 28, port 27, outlet chamber 25, port 26, passage 30 and passage 31, the compressor under this condition of operation serving merely to recirculate the fluid from the inlet side of the pump to the exhaust side of the pump and back again to the inlet side of the pump, without, however, supplying fluid to either of the reservoirs. Since the outlet chamber 25 is in constant communication with the low pressure reservoir 7 through the medium of conduit 29, the inlet side of the pump under this condition of operation will be at the same pressure as that obtaining in the low pressure reservoir, the escape of pressure from the inlet port to atmosphere being prevented by means of the check valve 17 as heretofore described.

A fluid pressure actuator system is also indicated which comprises a fluid motor 72 having a piston 73 slidably mounted therein and normally maintained at the left end of the motor by means of a spring 74. The piston is provided with a piston rod 75 connected thereto, and serving to actuate a lever 76, which in turn can control the operation of any desired device requiring power actuation for its control. The flow of fluid pressure to the motor 72 is controlled through the medium of a self-lapping control valve mechanism 77, which may preferably be constructed in accordance with the principles set forth in the patent to Wilfred A. Eaton, No. 2,204,530, dated June 11, 1940, this valve being provided with a control pedal 78, an inlet conduit 79 having a connection with the high pressure reservoir 6, an outlet conduit 80 having a connection with the fluid motor 72 and an exhaust conduit 81, it being understood, as more fully explained in the above referred to patent, that with the control pedal 78 in the position shown, communication is established between the outlet conduit 80 and the exhaust conduit 81, while on downward movement of the pedal, the latter communication will be broken off and communication will be estab-

lished between the inlet conduit 79 and the outlet conduit 80 to supply fluid pressure to the motor 72 in a degree dependent on the degree of displacement of the control pedal. Since the exhaust conduit 81 is connected at all times, as shown, to the low pressure reservoir 7, it will be apparent that with the valve in release position, the pressure in this conduit as well as the pressure in the outlet conduit 80 will be the same as that prevailing in the low pressure reservoir, and since this pressure is greater than atmospheric pressure, it is understood that the spring 74 is so tensioned as to insure the return of the piston 73 to the position shown against this pressure, this arrangement thus insuring complete release operation of the fluid motor 72 on release movement of the control pedal 78.

In the operation of this fluid pressure supply system, the parts are initially in the position shown when there is no pressure in either of the reservoirs, and on operation of the compressor, fluid at atmospheric pressure will be drawn into the inlet port through the atmospheric port 16, passage 15 and check valve 11 and after compression in the compressor, will be discharged to the high pressure reservoir through the discharge port 14, the check valve 22, the outlet chamber 20 and the conduit 21, this action continuing until such time as the pressure in the high pressure reservoir increases to a point where the governor 31 becomes operative to establish a connection between the conduit 40 and the conduit 41, whereupon fluid pressure is supplied to the fluid motor 42 through the medium of conduit 41, chamber 58, port 59, chamber 56, and conduit 57, and to the fluid motor 46 through conduits 41 and 67, the motors 42 and 46 thus becoming effective to move the beam 50 upward and to therefore move the valve 32 upward at the same time to a point where it closes off the port 26. When this occurs, the outlet chamber 25 will be placed in communication with the discharge port 14 through the passage 28 and the compressor will be conditioned to supply fluid pressure to the low pressure reservoir 7 through the conduit 29, the fluid again being drawn into the compressor through the atmospheric port 16 and past the check valve 11. When the fluid in the low pressure reservoir reaches the desired pressure, the governor 68 becomes operative to establish a connection between conduits 69 and 70, thus supplying fluid pressure to the upper end of the piston 64 in chamber 71, forcing the piston downward and causing the valve 63 to close the port 59 and open the port 61 to exhaust fluid pressure from the chamber 43 of the fluid motor 42 through conduit 57, chamber 56 and port 61, whereupon the spring 35 moves the valve 32 downward to mid-position, further movement of the valve to close the port 27 being prevented by the abutment of the piston 44 against the lower end of the fluid motor 42. Thus both the high and low pressure reservoirs are supplied with fluid compressed to the desired pressures and until leakage occurs from the system or fluid is used for the operation of the fluid motor 72, the discharge port 14 will be connected with the inlet port 13 through the passages already described and no further fluid will be pumped into either of the reservoirs.

If the control valve 77 is now operated to supply fluid pressure to the motor 72, it will be understood that after a number of such operations, the pressure in the high pressure reservoir 6 will be decreased to a point where the

governor 37 will become effective to break off communication between conduits 40 and 41 and establish communication between the conduit 41 and atmosphere, whereupon fluid pressure will be exhausted from chamber 47 of the motor 46 through conduits 61 and 41 permitting the spring 35 to move the valve 32 further downward to close the port 27, and since with the valve in this position, the outlet chamber 25 is connected with the inlet port 13 of the compressor as previously described, fluid pressure will be supplied to the inlet port from the low pressure reservoir 7 through conduit 29, outlet chamber 25, port 26, passage 30 and passage 31 to supercharge the compressor and to permit the compressor to pump fluid into the high pressure reservoir 6 through the discharge port 14, check valve 22, outlet chamber 20 and conduit 21, the supercharging of the inlet side of the compressor resulting in compressor operation at a comparatively low compression ratio to establish a relatively high pressure in the high pressure reservoir. This operation will of course deplete the fluid in the low pressure reservoir 7, and in the event the governor is set to operate on a 10 lb. range for example, it will be understood that when the pressure in the low pressure reservoir drops to 90 lbs., the governor 68 will become effective to dis-establish the connection between conduits 69 and 70 and to establish a connection between the conduit 70 and atmosphere to exhaust fluid pressure from the chamber 71 and permit the spring 66 to force the piston and the valve 63 upward again to a point where the valve closes the exhaust port 61 of the relay valve 38. When this action occurs, all the various parts will again be in the position shown on the drawing, and fluid from the low pressure reservoir will be compressed and pumped into the high pressure reservoir until such time as the governor 37 again acts to establish communication between conduits 40 and 41, at which time the valve 32 will be moved upward to open the port 27 and close the port 26, thus permitting the compressor to draw in fluid from the atmospheric port and compress it into the low pressure reservoir to replace that which has been pumped into the high pressure reservoir during the supercharging operation, and it will be understood that on continued operation of the mechanism, a condition of balance will be reached wherein there is a sufficient supply of fluid pressure in both the reservoirs and in the system to take care of all ordinary requirements of the mechanism controlled thereby, the governors thereafter being automatically effective to substantially maintain the proper pressure ratios between the low and high pressure sides of the system, the fluid returned to the low pressure reservoir from the fluid motor serves through conduit 80, valve 77 and conduit 81 being recirculated through the compressor and into the high pressure reservoir.

With reference to Fig. 2 of the drawings, another embodiment of the invention is illustrated, wherein the control valve mechanism actuated by the governors 37 and 68 is somewhat simplified, this embodiment including in general, a high pressure reservoir 6, a low pressure reservoir 7, a compressor 8 which may be of any suitable construction, the compressor being provided with an inlet port or conduit 13 and a discharge port or conduit 14. The inlet port 13 is provided with a connection to atmosphere which includes a passage 15 and an atmospheric port 16, communication between the inlet ports and the pas-

sage 15 being normally prevented by means of a check valve 17 normally maintained in engagement with the valve seat 18 formed at the lower end of the passage 15, through the medium of a spring 19 interposed between the casing and the lower face of the valve. The discharge port 14 is connected with the high pressure reservoir through the medium of an outlet chamber 20 and a conduit 21 interconnected between the chamber and the high pressure reservoir, a check valve 22 normally maintained in engagement with a valve seat 23 formed at the upper end of the discharge port 14, by means of a spring 24 interposed between the upper face of the valve and a portion of the casing, serving to permit passage of fluid from the compressor to the high pressure reservoir and to prevent the passage of fluid in the other direction from the reservoir to the discharge port of the compressor. A second outlet chamber 25 is provided as shown, this chamber being provided at its upper end with a port 26 and at its lower end with a port 27, the port 27 being connected with the discharge port 14 through the medium of a passage 28 formed in the casing. The second outlet chamber 25 is connected with the low pressure reservoir 7 through the medium of the conduit 29 while the port 26 at the upper end of the outlet chamber 25 is connected with the inlet port of the compressor through the medium of a passage 30 and a passage 31 formed in the casing and connected thereto. A valve 32 operable in the same manner as the similarly numbered valve in Fig. 1, serves to control the flow of fluid pressure through the ports 26 and 27, the valve being normally maintained in the position shown by means of a spring 35 mounted as heretofore described, the stem 33 of the valve having an operative connection with the beam 50 through the medium of a pivot pin 53. The operation of the governors 37 and 68 is identical with that previously described in connection with Fig. 1, the governor 37 serving on an increase of pressure in the reservoir 6 above a predetermined value to establish a connection between conduits 40 and 41, and the governor 68 serving on a similar increase in pressure in the reservoir 7 to establish a connection between conduits 69 and 70.

The beam 50 is mounted for actuation in a manner slightly different from that illustrated in Fig. 1, however, the right end of the beam being connected with a bracket 100, rigidly mounted with respect to the compressor 8 in any suitable manner, by a link 101 interconnected therebetween, the link being pivotally connected with the bracket 100 by means of a pivot pin 102 and to the right end of the beam 50 by means of a pivot pin 103. The left end of the beam 50 is adapted for actuation in either direction by a pair of fluid motors 104 and 105, these motors likewise being rigidly mounted with respect to the compressor as by means of a suitable bracket 106. The lower motor is provided with a cylinder 107 having a piston 108 slidably mounted therein, this piston being provided with an upwardly extending piston rod 109 adapted on upward movement to engage the lower face of the beam 50, the piston normally being maintained in the downward position shown through the medium of a spring 110 interposed between the upper end of the cylinder and the upper face of the piston, it being understood that with the piston in the position shown, there is sufficient clearance between the upper end of the rod 109 and the lower face

of the beam 50 to permit the spring 35 to move the valve 32 downward to fully closed position. The fluid motor 104 is provided with a fluid pressure chamber 111 below the piston, this chamber being connected with the conduit 41 leading to the high pressure governor 37, and it will be understood that the fluid motor is so proportioned that on the application of fluid pressure to the chamber 111, the piston will be moved upward, with the result that the rod 109 will move the beam 50 in a clockwise direction about the pivot pin 103 in an amount sufficient to move the valve stem 33 and the valve 32 upward to a point where the valve serves to close the port 26.

In order that the valve 32 may be moved to mid-position to unload the compressor, in the manner previously described in connection with the mechanism shown in Fig. 1, the upper fluid motor 105 is provided with a cylinder 112 having a considerably larger bore than the cylinder 101, together with a suitable piston 113 slidably mounted therein and provided with a downwardly extending piston rod 114 adapted on downward to engage the upper face of the beam 50 and to move the latter downward. The piston 113 is normally maintained in upward position by means of a spring 115 interposed between the lower end of the cylinder and the lower face of the piston, and the downward movement of the piston is limited to substantially half that of the piston in the fluid motor 104 by means of a stop 116 formed on the lower face of the piston and adapted on downward movement thereof to engage the end of the cylinder. The upper end of the fluid motor is provided with a fluid pressure chamber 117 having a connection with the conduit 70 leading to the low pressure governor 68, and the area of the piston with respect to the piston of the lower motor is so proportioned that on the application of pressure to the chamber 117 on operation of the governor 68 to supply fluid pressure to the motor, the force exerted by the piston 113 in the downward direction is sufficient to overcome the upward force exerted by the piston 108 of the motor 104, the result being that, due to the restricted stroke of the fluid motor 105, the beam 50 is moved downward sufficiently to cause the valve 32 to move to mid-position so that the outlet port 14 of the compressor is connected with the inlet port 13 through the passage 28, port 27, outlet chamber 25, port 26, passage 30 and passage 31, the compressor thus being unloaded and the pumping of fluid pressure to either of the reservoirs being prevented with the valve in this position.

When the system is initially placed in operation with atmospheric pressure in the reservoirs, the parts are in the position shown, and on starting of the compressor 8, fluid pressure will be drawn into the inlet port 15 past the check valve 17, and after compression, supplied to the high pressure reservoir through the discharge port 14, the check valve 22, the outlet chamber 20 and the conduit 21, it being understood that when the pressure in the reservoir 6 reaches a predetermined value, the governor 37 becomes operative to establish a connection between conduits 40 and 41 to supply fluid pressure to the fluid motor 104 through the conduit 41, thus forcing the piston 108 upward and moving the beam 50, the valve stem 33 and the valve 32 upward to their fullest extent in order to effect closure of the port 26 in the outlet chamber 25, thus permitting fluid drawn into the intake of the compressor from atmosphere to be pumped into the low pressure

reservoir 7 through the outlet passage 14, passage 28, port 27, outlet chamber 25 and conduit 29. When the pressure in the reservoir 7 reaches a predetermined value, the governor 68 will become effective to establish a connection between conduits 69 and 10, thus supplying fluid pressure through the conduit 10 to the chamber 117 of the fluid motor 105, the resulting pressure on the enlarged area of the piston 113 being sufficient to overcome the upward force exerted by the piston 108 and to force the beam 50 downward until the stop 116 engages the lower end of the cylinder, whereupon the valve 32 will be in mid-position and the discharge port of the compressor will be connected with the inlet port through passage 28, port 27, outlet chamber 25, port 26, passage 30 and passage 31, and the compressor will be in the unloaded condition. During this cycle of operation, it is understood that fluid pressure will be supplied to both of the motors 104 and 105, operation of the governor 31 to dis-establish the connection between conduits 40 and 41 and to establish a connection between the conduit 41 and atmosphere serving to disestablish the connection between conduits 40 and 41 and to connect the latter with atmosphere, thus exhausting fluid pressure from the motor 104 and permitting the spring 35 to return the valve 32 to the position shown, while operation of the governor 68 to dis-establish the connection between conduits 69 and 70 and to establish a connection between the conduit 70 and atmosphere while fluid pressure is being supplied to the motor 104 by the governor 31, will serve to deenergize the motor 105 and permit the piston of the motor 104 to move the beam 50 upward to move the valve 32 to its extreme upward position. Thus the control exerted on the operation of the valve 32 by the governors 31 and 68 is substantially similar to that obtained in the mechanism shown in Fig. 1, but a somewhat simplified construction is obtained through the elimination of the relay valve mechanism 38.

There have thus been provided in the two embodiments of the invention illustrated and described, a control mechanism for a compressor of the single-stage type, so constituted as to automatically maintain one pressure in a high pressure reservoir and a lower pressure in another reservoir, together with means for supercharging the compressor with fluid from the low pressure reservoir in order to permit charging of the high pressure reservoir by means of a single-stage compressor without utilizing a compression ratio high enough to result in excessive heating conditions such as are ordinarily encountered under conditions of this kind, thus making it possible to maintain a much higher pressure difference between the high and low pressure sides of the system with a single-stage compressor than would be possible in systems of the type heretofore utilized.

While the two illustrated embodiments of the invention have been shown and described with considerable particularity, it is to be understood that the invention is not limited thereto, but may be embodied in a variety of expressions as will be understood by those skilled in the art. Reference will, therefore, be had to the appended claims for a definition of the limits of the invention.

What is claimed is:

1. The combination in a fluid pressure supply system having a high pressure reservoir, a low pressure reservoir and a compressor for supplying fluid pressure to said reservoirs, of means

for controlling the operation of said compressor for supplying fluid pressure to one or the other of said reservoirs, means controlled by the pressure in the low pressure reservoir for controlling the operation of said first named means for preventing the compressor from supplying fluid pressure to either of said reservoirs, and means controlled by the pressure in said high pressure reservoir for controlling the operation of said first named means for permitting the compressor to supply fluid pressure to the low or high pressure reservoir dependent on the degree of pressure in the latter reservoir.

2. The combination in a fluid pressure supply system having a high pressure reservoir, a low pressure reservoir and a compressor for supplying fluid pressure to said reservoirs, of means for controlling the operation of said compressor for directing the fluid pressure supply therefrom to one or the other of said reservoirs, means controlled by variations of pressure in said high pressure reservoir for rendering said first named control means effective to direct the supply of fluid pressure to said low pressure reservoir, and means controlled by variations of pressure in said low pressure reservoir for rendering said first named control means effective for preventing the flow of pressure to either of said reservoirs.

3. The combination in a fluid pressure supply system having a high pressure reservoir, a low pressure reservoir, and a compressor having an inlet port and a discharge port, of means for connecting said discharge port with the high pressure reservoir, means for connecting said discharge port with the low pressure reservoir, means for connecting said inlet and discharge ports, and means controlled by variations of pressure in both of said reservoirs for controlling the operation of said connecting means whereby the pressure in both of said reservoirs is normally maintained at a pressure higher than atmospheric pressure and the pressure in said high pressure reservoir is maintained at a pressure higher than that in the low pressure reservoir.

4. The combination in a fluid pressure supply system having a pair of reservoirs and a compressor having an inlet port and a discharge port, of means for connecting the discharge port selectively with either of said reservoirs for supplying fluid pressure thereto, means for connecting the discharge and inlet ports for preventing said compressor from supplying fluid pressure to either of said reservoirs, and means controlled by variations in pressure in both of said reservoirs for controlling the operation of said connecting means.

5. The combination in a fluid pressure supply system having a pair of reservoirs and a compressor having inlet and discharge ports, of means for normally connecting said discharge port with one of said reservoirs for supplying fluid pressure thereto from the compressor, means for preventing the flow of fluid pressure from said one reservoir to said discharge port, means for connecting said inlet port with the other reservoir for receiving fluid pressure therefrom, means for connecting the discharge port with said other reservoir for supplying fluid pressure thereto, and means controlled by variations of pressure in said one reservoir for controlling the operation of said connecting means.

6. The combination in a fluid pressure supply system having a pair of reservoirs and a compressor for supplying fluid pressure thereto hav-

ing inlet and discharge ports, of means including a control valve operable for selectively connecting said discharge port with one of said reservoirs or with said inlet port, means for connecting said discharge port with said other reservoir, and means controlled by variations of pressure in both of said reservoirs for controlling the operation of said first named control means.

7. The combination in a fluid pressure supply system having a pair of reservoirs and a compressor provided with inlet and discharge ports for supplying fluid pressure to said reservoirs, of means including a valve for controlling the flow of fluid pressure between said ports and between said ports and reservoirs for rendering the compressor effective to supply fluid pressure to either of said reservoirs and for rendering said compressor ineffective to supply fluid pressure to either of said reservoirs, and means responsive to variations in pressure in both of said reservoirs for controlling the operation of said means.

8. The combination in a fluid pressure supply system having a pair of fluid pressure reservoirs and a compressor for supplying fluid pressure thereto having inlet and discharge ports having a connection therebetween and connections with said reservoirs, of means for controlling the connection between said ports and for controlling the connections between said ports and reservoirs for selectively establishing a connection between the discharge port and the low pressure reservoir, between the low pressure reservoir and the inlet port and between the discharge port and the inlet port, and means responsive to variations of pressure in said reservoirs for controlling the operation of said connection controlling means.

9. The combination in a fluid pressure supply system having a pair of reservoirs and a compressor for supplying fluid pressure thereto, said compressor being provided with inlet and discharge ports, of means for connecting said discharge port with one of said reservoirs, means including a valve operable in one position for establishing a connection between said other reservoir and said inlet port, operable in another position for establishing a connection between said discharge port and inlet port and operable in the third position for establishing a connection between said inlet port and said other reservoir, and means controlled in response to variations of pressure in both of said reservoirs for controlling the operation of said valve to establish said connections, whereby the pressure in said one reservoir is maintained at a pressure higher than that in said other reservoir and the pressure in said other reservoir is maintained at a pressure above atmospheric pressure.

10. The combination in a fluid pressure supply system having a high pressure reservoir, a low pressure reservoir and a compressor provided with an inlet port and a discharge port for supplying fluid pressure to said reservoirs, of means for connecting said discharge port with said high pressure reservoir, means for preventing the flow of fluid pressure through said connecting means from said high pressure reservoir to said discharge port, means responsive to variations of pressure in said high pressure reservoir and operable when the pressure therein exceeds a predetermined value for establishing a connection between said discharge port and low pressure reservoir, means controlled by variations in pressure in said low pressure reservoir

and operable when the pressure therein exceeds a predetermined value for controlling the operation of said connection establishing means to establish communication between the low pressure reservoir and the inlet port of the compressor whereby the fluid pressure in the low pressure reservoir is recompressed by the compressor and delivered to the high pressure reservoir, an atmospheric connection associated with said inlet port, and means for preventing the escape of fluid pressure from said inlet port to atmosphere when said low pressure reservoir is connected with the inlet port of the compressor.

11. The combination in a fluid pressure supply system having a pair of reservoirs and a compressor having inlet and discharge ports, of means for connecting said discharge port with either of the reservoirs for supplying fluid pressure thereto and for connecting the inlet port with one of the reservoirs for receiving fluid pressure therefrom, and means controlled by variations of pressure in the other of said reservoirs for controlling the operation of said connecting means.

12. The combination in a fluid pressure supply system having a pair of reservoirs and a compressor having inlet and discharge ports, of means for connecting the discharge port with one of the reservoirs, means including a valve operable in one position for connecting said other reservoir and inlet port, in another position for connecting said inlet and discharge ports, and in a third position for preventing communication between said other reservoir and inlet port, and means for controlling the operation of said valve and for moving the latter to said positions including a fluid actuator responsive to variations of pressure in said one reservoir and a second fluid actuator responsive to variations of pressure in said other reservoir.

13. The combination in a fluid pressure supply system having a pair of reservoirs and a compressor having inlet and discharge ports, of means for connecting the discharge port with one of the reservoirs, means including a valve operable in one position for connecting said other reservoir and inlet port, in a second position for connecting said inlet and discharge ports, and in a third position for preventing communication between said other reservoir and inlet port, means for normally maintaining said valve in the first named position, means including a pair of fluid actuators controlled by the pressure in said one reservoir for moving the valve to said third position, and means controlled by the pressure in the other reservoir for deenergizing one of said actuators and permitting movement of the valve to said second position under the action of said maintaining means.

14. The combination in a fluid pressure supply system having a pair of reservoirs and a compressor having inlet and discharge ports, of means for connecting the discharge port with one of the reservoirs, means including a valve operable in one position for connecting said other reservoir and inlet port, in a second position for connecting said inlet and discharge ports, and in a third position for preventing communication between said other reservoir and inlet port, means for normally maintaining said valve in the first named position, means including a fluid actuator responsive to the pressure in said one reservoir for moving the valve to said third position when the pressure in said one reservoir exceeds a predetermined value, and means in-

cluding a fluid actuator responsive to the pressure in said other reservoir for opposing the action of said first named actuator and moving the valve to said second position when the pressure in said other reservoir exceeds a predetermined value.

15. The combination in a fluid pressure supply system having a pair of reservoirs and a compressor having inlet and discharge ports, of means for connecting the discharge port with one of the reservoirs, means including a valve operable in one position for connecting said other reservoir and inlet port, in a second position for connecting said inlet and discharge ports, and in a third position for preventing communication between said other reservoir and inlet port, means for normally maintaining said valve in the first named position, a fluid actuator for moving the valve to the third position, a second fluid actuator for moving the valve from the third to the second position, means controlled by variations of pressure in said one reservoir for supplying fluid pressure to the first named actuator when the pressure in said one reservoir exceeds a predetermined value, and means controlled by variations of pressure in said other reservoir for supplying fluid pressure to said second actuator when the pressure in said other reservoir exceeds a predetermined value.

16. The combination in a fluid pressure supply system having a pair of reservoirs and a compressor having inlet and discharge ports, of means for connecting the discharge port with one of the reservoirs, means including a valve operable in one position for connecting said other reservoir and inlet port, in a second position for connecting said inlet and discharge ports, and in a third position for preventing communication between said other reservoir and inlet port, means for normally maintaining said valve in the first named position, a pair of fluid actuators for moving the valve to said third position, valvular means controlled by variations of pressure in said one reservoir for supplying fluid pressure to said actuators to move the valve to said third position when the pressure in said one reservoir exceeds a predetermined value, and means controlled by variations of pressure in said other reservoir for preventing the supplying of fluid pressure to one of said actuators by the operation of said valvular means when the pressure in said other reservoir exceeds a predetermined value for permitting

movement of said valve to said second position by said maintaining means.

17. The combination in a fluid pressure supply system having a pair of reservoirs and a compressor having inlet and discharge ports, of means for connecting the discharge port with one of the reservoirs, means including a valve operable in one position for connecting said other reservoir and inlet port, in a second position for connecting said inlet and discharge ports, and in a third position for preventing communication between said other reservoir and inlet port, means for normally maintaining said valve in the first named position, a pair of fluid actuators for moving the valve to said third position, valvular means controlled by variations of pressure in said one reservoir for supplying fluid pressure to said actuators to move the valve to said third position when the pressure in said one reservoir exceeds a predetermined value, a fluid pressure operated valve for controlling the supplying of fluid pressure to one of said actuators by the operation of said valvular means, and means controlled by variations of pressure in said other reservoir for supplying fluid pressure for operating said control valve when the pressure in said other reservoir exceeds a predetermined value.

18. The combination in a fluid pressure supply system having a pair of reservoirs, a compressor for supplying fluid pressure thereto and connections between the compressor and both of said reservoirs, of control means for controlling said connections for permitting the supplying of a different predetermined pressure to each of said reservoirs and for preventing the supplying of fluid pressure to either reservoir when said predetermined pressures are established, and means controlled by variations of pressure in both reservoirs for controlling the operation of said control means.

19. The combination in a fluid pressure supply system having high and low pressure reservoirs and a fluid pump, of means for selectively connecting the pump to pump fluid to the high pressure reservoir, to pump fluid to the low pressure reservoir, to pump fluid from the low pressure reservoir to the high pressure reservoir, and to prevent the pumping of fluid to either of the reservoirs, and means controlled by variations of pressure in said reservoirs for controlling the operation of said connecting means.

ELBERT FOWLER.
